(57) **CLAIM**

The ornamental design for a display screen or portion thereof with graphical user interface, as shown and described.

DESCRIPTION

The sole FIGURE is a display screen or portion thereof with graphical user interface.

The broken lines (including broken text or numbers) shown in the FIGURE are for environmental purposes only and form no part of the claimed design. In particular, broken portions of text (letters and numbers) in the graphical user interface, and the display screen on or in which the graphical user interface is embodied, are shown in broken lines or characters for environmental purposes and form no part of the claimed design.
